1

This invention relates to relays and relay circuits and control systems including the same.

One object of the invention is a novel and improved relay and relay control for starting a gaseous discharge device.

More particularly the invention is particularly applicable to the starting of conventional fluorescent lamps wherein at starting a relatively large value of current flows and it is required that the control be adjusted to delay its action for approximately one second or longer and, on the other hand, the contacts be held open during normal operation of the lamp notwithstanding the reduction in current flowing during normal operation of the lamp.

An object of the invention is a simple and inexpensive starting control for lamps of this character which is characterized by operative functioning to accord exactly with the demands of a starter of this character.

A further object of the invention is a novel and improved thermal starting control of the above indicated character.

A further object of the invention is a novel and improved magnetic control of the above indicated character.

A further object of the invention is a novel and improved starting control of the above indicated character for a normally closed starting circuit.

A further object of the invention is a starting control of the above indicated character for a normally open starting circuit.

A further object of the invention is a novel and improved relay and relay control.

Further objects of the invention will herein-after appear.

For a better understanding of the invention reference may be had to the accompanying drawings wherein

Fig. 1 is a diagram of a relay circuit illustrating the principle of the invention;

Fig. 1A is a circuit diagram of a control system embodying the modification of Fig. 1;

Fig. 2 is a diagram illustrating the modified relay embodying the principle of the invention;

Fig. 2A is a circuit diagram of a control system embodying the modification of Fig. 2;

Fig. 2B is a graph illustrating the functioning of a relay embodying the invention of Figs. 2 and 2A;

Fig. 3 is a circuit diagram of a modified starting means for gaseous discharge lamps.

Referring to Fig. 1 of the drawings, I have illustrated one embodiment of my improved relay

comprising switch control contacts 10 which are thermally controlled, the details of the thermal mechanism being omitted for convenience in illustration. The thermal mechanism is controlled by a heater element 11 which is energized by the current flowing in the circuit 14, 15. A resistance element 20 is connected in parallel with the heater element 11. The heater element 11 of the thermal relay is made of a material or metal with a high positive temperature coefficient of resistance, as for example of a wire of tungsten, iron, nickel, etc. which have positive temperature coefficients of resistance. The resistance element 20 has very little or no positive temperature coefficient, as for example, being made of a wire of a metal such as Nichrome which has little or no resistance change with changes in temperature or changes in volume of current flowing. The action is such that there will be less percentage change of current through the heater element 11 for any change of current flowing in the circuit 14, 15 than there would be without this particular arrangement. This occurs because of the large change in resistance in the heater element 11 with changes in current due to its positive temperature coefficient of resistance, that is with increase in current there is an increase in temperature which causes the resistance of the heater element 11 to become greater, thereby causing a greater percentage or proportion of the total current flowing in the circuit 14, 15 to flow through the shunt resistor 20 and vice versa. By making the shunt resistor element 20 of some material, alloy or metal which has a negative temperature coefficient of resistance, such as carbon, or which has negative resistance characteristics such as certain of the silicon carbide compounds, namely by having the resistance of the shunt element 20 vary inversely with respect to the resistance of the heater element 11 a still greater differential in the current flowing in the two elements is obtained with changes in the total current flowing. With this arrangement changes in the total current flowing in the circuit 14, 15 are reflected to a substantially lesser extent in the element 11, that is the percentage change in the current flowing in the element 11 is substantially less than the percentage change in the total current flowing.

The invention is particularly applicable to the starting of gaseous discharge devices, such for example, as the fluorescent lamp A illustrated in Fig. 1A.

55 The fluorescent lamp A is provided with the

conventional heating elements 12 at each end of the tube and in the conventional manner the heaters 12 of the lamp are connected in series with a conventional transformer choke 13. The heater element 11 of the thermal relay is connected in series with the line 14 from one side of the circuit, the line 15, the two heating elements 12 and the line 16 leading to the other end of the choke coil 13. The heaters 12 are connected on one side by the wires 17 to the switch contacts 10 of the thermal relay and a conventional condenser 18 is shown connected across the switch contacts 10. The switch contacts 10 are normally closed, that is closed when the line switch 19 is open or the lamp A is not operating. When the line switch 19 is closed starting current flows through the circuit, heating the filaments 12 at each end of the lamp and also the heater element 11 of the thermal relay. After a suitable time delay the contacts 10 of the relay snap open and if the lamp lights by discharge between the elements 12 these switch contacts 10 are retained open due to the running current of the lamp which flows through the heater element 11 of the relay.

This control is effected notwithstanding the large change in the volume of current flowing in going from starting condition to the running condition, for example with .8 of an ampere flowing at the initial starting the time delay of say, one second, for heating the heaters 12 may be obtained before the switch contacts 10 are opened and even though the current flowing in the circuit during the normal operation of the lamp should drop to half or below, say to .25 ampere for normal running, the heater element is supplied with a sufficient current to hold the contacts 10 open against the bias tending to close them.

Any suitable type of thermal switch may be employed as for example the bimetallic type or the vane type. In either case the heating element 11 is preferably enclosed in an evacuated envelope 11' so as to prevent oxidation of the element at high temperatures at which the element should be run for best results. An example of the vane type of switch which may be used is illustrated in Fig. 8 of Schmidinger Patent 2,133,309 wherein the switch contacts 39 and 44' are the contacts 10 of this application and the heater element 43 is the heating element 11 of the application.

A modified relay and circuit control is illustrated in Fig. 2. The circuit is indicated at 14, 15, the thermal relay contacts are indicated at 10 and the heating element for the thermal switch device is indicated at 21. The heater 21 has connected in series with it a resistance element 25 having a positive temperature coefficient such for example as of tungsten, nickel or iron and a resistance element 20 is connected in shunt of the character described above with respect to Fig. 1 and Fig. 1A. For example, the resistance element 20 may be of Nichrome or other resistor element with a fairly constant resistance with temperature changes, or it may have a negative coefficient, and as indicated, the series combination consisting of the resistor element 25 and the heater element 21 of the thermal relay is connected in parallel with the element 20. The element 25 is placed in an evacuated envelope such as the envelope 11' of Fig. 1A so that it is not oxidized or harmfully affected in any manner when heated to a red or white heat. The action of this control is to allow a greater percentage of the total current flowing to pass through the

heater element of the thermal relay, when the total current is low in value than at higher values of total current, namely at low values of current the element 25, such for example as of tungsten wire, has a proportionately low value of electrical resistance. At higher values of current the resistance of the tungsten element increases at a much greater proportionate rate than the resistance of the other elements of the circuit which decreases the proportional amount of the total current that flows in the path composed of the tungsten heater element 25 and the heater element 21. The heater element 21 is of course of a character so as not to oppose the controlling function of the element 25, namely the element 21 must not have an appreciable negative coefficient at least in sufficient amount taking into consideration the proportions of the resistance elements 21 and 25 to offset the stabilizing effect of the element 25 with changes in total current flowing. The element 20 is a resistance either having no appreciable positive temperature coefficient or one having a negative coefficient. In the circuit of Fig. 2 and Fig. 2A, the temperature coefficient 25 of the heater 21 as indicated need not be a high temperature coefficient since the element 25 imparts the desired high temperature coefficient characteristic to the circuit including the heater 21.

Fig. 2B illustrates graphs of the currents flowing in the heater branch of the parallel circuit and in the shunt or ballast branch containing the element 20. The abscissas represent total currents and the ordinates represent the current flowing in each of these branches. The lower curve represents the current flowing through the heater 21 and the tungsten resistor element 25 and the upper curve represents the current flowing in the ballast or shunt circuit containing the resistor element 20. This shows that with changes in total current flowing the percentage change in the heater branch of the circuit is much smaller than the changes in the total current flowing, thereby rendering the thermal switch mechanism much less sensitive to changes in current flow. For example, for values of total current above 0.25 ampere with the particular combination of resistances upon which the graphs are based the current in the heater element branch changes only a slight amount for much larger variations in the total current flowing. These graphs are based upon the test results of a circuit in which the element 21 was a pull wire 55 in a vane type thermostatic switch made of 0.0065 Ohmax, the element 25 was a standard T67 lamp and the element 20 was of 17.82 .010 Nichrome wire. The graphs indicate that the operational range of such a control unit can be increased greatly without substantially affecting its operation. For example, it can be effectively used to control any fluorescent lamp within a wide range of capacities, as for example, fluorescent lamps of capacities from 15 watts to 40 watts 60 sizes. For example, it is found by actual test that the operating time for the thermal switch was 0.82 second at 0.37 ampere total current and 3.07 seconds at 0.488 ampere total circuit current.

In Fig. 2A I have illustrated the embodiment 70 of the invention of Fig. 2 as used in the starting of a fluorescent lamp similar to that illustrated in Fig. 1. In this embodiment the operating or heater element 21 for the relay contacts 10 has connected in series with it a resistance element 25 having a positive temperature resistance co-

efficient such as that of tungsten, iron, nickel or other material having such a characteristic. A Nichrome or other resistor element 20 having a fairly constant resistance with temperature and current changes is connected in shunt with the series combination consisting of the element 25 and the heater element 21 of the thermal relay. The element 25 is preferably placed in an evacuated or gas-filled container such as the container 11' described above in Fig. 1A or else is otherwise protected in any suitable manner so as not to be oxidized or harmfully affected in any manner when heated to red or white heat. The action of this arrangement is to allow a greater percentage of the total current flowing to pass through the element 21 of the relay when the total current is low in value than at higher values of current. At low values of current the element 25 has a proportionately low value of electrical resistance, whereas at higher values of current the resistance of the element 25 increases at a much greater proportional rate than the resistances of the other elements of the circuit. This decreases the proportional amount of total current that flows in the path composed of the tungsten resistance 25 in series with the relay heater filament.

The operation generally of the control of Fig. 2A is similar to that described above with respect to Fig. 1A, namely after the starting of the fluorescent lamp A the heating element 21 has sufficient power to hold the contacts 10 open notwithstanding the reduced flow of current through the circuit 14 and 15 when the lamp is operating. The heater element 21 may be a pull wire or the heater element of a thermal switch, such for example, as that shown in Fig. 8 of the Schmidinger Patent 2,133,309 wherein the switch contacts 39 and 44' are the contacts 10 of this application and the heater element 43 is the heating element 21 of the application, or the element 21 may be the pull wire itself.

Fig. 3 shows a modified control for the starting of a gaseous discharge device A. This gaseous discharge device is illustrated as of the conventional fluorescent lamp type having a heater electrode 12 at either end thereof. The supply line is indicated as having a choke coil 13 connected in one side thereof and the line as connected with one end of the heater electrodes 12. The other ends of the heaters 12 are connected through the lines 30 and 31 with the contacts 3' of the thermostatic switch. The contacts 3' are normally open, biased to open position, namely open when the switch 19 in the supply line is open and also open during the normal operation of the fluorescent lamp A. These contacts 3' however are closed momentarily at starting by the heat delivered by the element 4. The element 4 is a heater of a metal having a high positive temperature coefficient, such as tungsten, iron or nickel, etc. and the element 5 is a resistance either having no appreciable positive temperature coefficient, such as of Nichrome or having a negative temperature coefficient, such as carbon or the silicon carbide compounds. The resistance of element 5 is much larger than that of resistance 4 so as to predominate thereover, as for example being 75% to 90% of the sum of the two. During the normal operation of the lamp the elements 4 and 5 are connected across the electrode heaters 12 and accordingly the voltage drop across the lamp A is supplied to these two elements in series. The I^2R power of the element 4 is insufficient to close the contacts 3' with only

the voltage drop of the lamp A applied to the elements 4 and 5. At starting, however, namely when the switch 19 is first closed substantially the full line voltage (115 v.) is supplied to the resistances 12 and the elements 4 and 5 and the heating power of the element 4 is then very substantially increased by reason of the relative proportioning and character of the two elements 4 and 5 as described above. This increased power results in the closing of the contacts 3' and the short-circuiting of the elements 4 and 5 and the consequent reopening of the contacts 3' which are biased to the open position against the heating effect of the element 4. The short-circuiting of the elements 4 and 5 puts the heaters 12 directly across the line with the resultant increased heating of these electrodes so that when the contacts 3' are opened after the momentary closure thereof the desired starting kick is delivered to the lamp A. The voltage drop, as indicated, in the lamp A is then insufficient to close the contacts 3' against the bias. Thus by rendering the thermal switch sensitive to the full line voltage but not sensitive to the voltage drop across the lamp A to close the contacts 3' a very simple and inexpensive starting mechanism is provided for the lamp. A conventional condenser 18 is connected across the contacts 3'.

I claim:

- 30 1. In a control means for a gaseous discharge device having heating elements therein, a circuit connecting said heaters in series across a supply line, a switch in said circuit which is thermally controlled, a controlling element for said switch which is energized by the current flowing through said circuit and through the gaseous device, a resistor element in parallel with said controlling element, the coefficients of said elements being related to each other in a manner to differentially proportion variations in the current flowing in the circuit to shift greater changes in current flow to the resistor element.
- 35 2. In a control means for a gaseous discharge device having heating elements therein, a circuit connecting said heaters in series across a supply line, a switch in said circuit which is thermally controlled, a controlling element for said switch which is energized by current flowing through said circuit and through the gaseous device, a resistor element in parallel with said controlling element, the coefficients of said elements being related to each other in a manner to differentially proportion variations in the current flowing in the circuit to shift greater changes in current flow to the resistor element.
- 40 3. In a control means for a gaseous discharge device having heating elements therein, a circuit connecting said heaters in series across a supply line, a switch in said circuit which is thermally controlled, a controlling element for said switch which is energized by current flowing through said circuit and through the gaseous device, a resistor element in parallel with said controlling element, the coefficients of said elements being related to each other in a manner to differentially proportion variations in the current flowing in the circuit to shift greater changes in current flow to the resistor element, said switch being opened by the current flowing through the operating element.
- 45 4. In a control means for a gaseous discharge device having heating elements therein, a circuit connecting said heaters in series across a supply line, a switch in said circuit which is thermally controlled, a controlling element for said switch which is energized by current flowing through said circuit and through the gaseous device, a resistor element in parallel with said controlling element, the coefficients of said elements being related to each other in a manner to differentially proportion variations in the current flowing in the circuit to shift greater changes in current flow to the resistor element.
- 50 5. In a control means for a gaseous discharge device having heating elements therein, a circuit connecting said heaters in series across a supply line, a switch in said circuit which is thermally controlled, a controlling element for said switch which is energized by current flowing through said circuit and through the gaseous device, a resistor element in parallel with said controlling element, the coefficients of said elements being related to each other in a manner to differentially proportion variations in the current flowing in the circuit to shift greater changes in current flow to the resistor element, said switch being opened by the current flowing through the operating element.
- 55 6. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 60 7. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 65 8. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 70 9. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 75 10. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 80 11. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 85 12. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 90 13. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.
- 95 14. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element.

device having heating elements therein a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow so as to cause a smaller variation of current flowing through the thermal element than that flowing through the resistor element.

5. In a control means for a gaseous discharge device having heating elements therein a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow, the thermal element having a positive temperature resistance coefficient and the resistor element having no appreciable positive temperature resistance coefficient.

6. In a control means for a gaseous discharge device having heating elements therein, a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow to shift greater changes in current flow to the resistor element, a resistance having a high temperature resistance coefficient being connected in series with the thermal element.

7. In a control means for a gaseous discharge device having heating elements therein, a circuit connecting said heaters in series across a supply line, a normally open switch in said circuit, thermal means for closing said switch at the starting of the gaseous discharge device comprising a heating element and a resistor element connected across said switch, said switch heating element being of a substantially smaller resistance than that of the series resistor and said heater having a positive temperature coefficient of resistance and said resistor element having no appreciable positive temperature coefficient of resistance.

8. In a control means for a gaseous discharge device having heating elements therein a circuit connecting said heaters in series across a supply line, a switch in said circuit which is thermally controlled, a thermal element for controlling said switch which is energized by part of the current flowing through said circuit and through the

gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow with the resistance of the circuit which is in multiple with said resistor element having a high positive temperature coefficient and with the resistor element having little or no positive temperature coefficient.

9. In a control means for a gaseous discharge device having heating elements therein a circuit connecting said heaters in series across a supply line, a switch in said circuit which is thermally controlled, a thermal element for controlling said switch which is energized by part of the current flowing through said circuit and through the gaseous device, and a resistor element connected in multiple with a circuit including said thermal element so as to be energized by a part of the current flowing in said first-named circuit with the resistances of the multiple paths of the currents through the two elements varying differentially with respect to each other upon variations of current flow with the resistance of the circuit which is in multiple with said resistor element having a high positive temperature coefficient.

10. Starting means for a discharge lamp having a pair of starting filaments adapted to be connected across a supply line during the starting operation, the combination of a thermally controlled two-position switch in series with the filaments adapted in one position to energize them for starting, a thermal element having a high positive temperature coefficient of resistance connected in series with the filaments for operating the switch at starting, and a resistor having no appreciable positive temperature coefficient of resistance connected with the thermal element, said resistor and element being continuously in circuit with the supply line to be heated thereby during both starting and normal operation with the heating current through the thermal element during normal operation of the lamp being substantially lower than that during starting.

11. Starting means for a discharge lamp having a pair of starting filaments adapted to be connected across a supply line during the starting operation, the combination of a thermally controlled two-position switch in series with the filaments adapted in one position to energize them for starting, a thermal element having a high positive temperature coefficient of resistance connected in series with the filaments for operating the switch at starting, and a resistor having no appreciable positive temperature coefficient of resistance connected with the thermal element, said resistor and element being continuously in circuit with the supply line to be heated thereby during both starting and normal operation with the heating current through the thermal element during normal operation of the lamp being substantially lower than that during starting, the switch being normally open.
